UNITED STATES PATENT OFFICE.

LAYTON EUGENE CROE AND FRED L. MILLER, OF KALAMAZOO,
MICHIGAN.

CHIMNEY OR STACK.

SPECIFICATION forming part of Letters Patent No. 791,452, dated June 6, 1905.

Application filed August 4, 1904. Serial No. 219,558.

To all whom it may concern:

Be it known that we, LAYTON EUGENE CROE and FRED L. MILLER, citizens of the United States, residing in the city of Kalamazoo, county of Kalamazoo, State of Michigan, have invented certain new and useful Improvements in Chimneys or Stacks, of which the following is a specification.

This invention relates to improvements in chimneys or stacks.

The objects of this invention are, first, to provide an improved chimney or stack which is practically fireproof and also an effective ventilator; second, to provide an improved chimney or stack having the advantages above stated in which the parts are economical to produce and quickly and economically assembled.

Further objects and objects relating to structural details will definitely appear from the detailed description to follow.

We accomplish the objects of our invention by the devices and means described in the following specification.

The invention is clearly defined and pointed out in the claims.

A structure embodying the features of our invention is clearly illustrated in the accompanying drawings, forming a part of this specification, in which—

Figure 1 is a detail side elevation view of a structure embodying the features of our invention, portions of a building being illustrated in section to show the relation of the parts. Fig. 2 is an enlarged detail vertical sectional view taken on a line corresponding to line 2 2 of Fig. 1. Fig. 3 is a detail transverse sectional view taken on a line corresponding to line 3 3 of Fig. 2. Fig. 4 is a transverse sectional view taken on a line corresponding to line 4 4 of Fig. 2, showing the arrangement of the combined pipe-opening or thimble and ventilator. Fig. 5 is an enlarged detail vertical sectional view of the upper portion of a chimney, taken on a line corresponding to line 5 5 of Fig. 2, showing the outlet openings for the air or ventilator passages. Fig. 6 is a side elevation view of one of the outer-wall sections or blocks. Fig. 7 is a per-

spective view of one of the pieces B used for cap and base.

In the drawings the sectional views are taken looking in the direction of the little arrows at the ends of the section-lines, and similar letters of reference refer to similar parts throughout the several views.

Referring to the drawings, our improved chimney or stack is made up of an outer or exterior wall and an interior wall forming the smoke-flue. The exterior wall is of such size that when the interior wall or smoke-flue is placed within air passages or chambers are formed about the same within the exterior wall. The outer or exterior wall is made up of rectangular tile-like blocks of artificial stone, concrete, or the like. These blocks are preferably made of suitable Portland-cement composition. These exterior-wall blocks are secured together and their joints sealed by laying them in cement, so that when a chimney is constructed it is, in effect, one continuous artificial-stone wall.

The exterior wall of the chimney is made up mainly of the plain rectangular hollow blocks A.

Modified forms of the blocks A, as A' A'' A''' A''', are provided, the purpose of which will fully appear as their relations are pointed out.

The outer-wall sections are provided with oppositely-arranged inwardly-facing curved seats s, adapted to receive the tubular sections D, of which the inner wall or smoke-flue is made up. These sections D are also preferably made of a suitable artificial stone or concrete.

Cap and base pieces B are provided. These cap and base pieces have central openings b therethrough and inwardly-extending projections b'. These projections b' are conformed to fit within the outer wall and about the inner wall, thus firmly securing the parts in position and sealing the ends of the air passages or chambers about the smoke-flue. The cap and base pieces are identical in form, so that they may be formed in the same mold. In constructing a chimney or stack the base-piece is placed in an inverted position upon the

chimney-foundation, as C. This foundation may be made of masonry, as illustrated, or of concrete, as may be desired. The foundation C is provided with a suitable chamber 5 to receive the clean-out receptacle C'. (See Fig. 2.)

The sections forming the outer and inner walls are arranged so that they overlap or break joints, thus adding to the strength of 10 the chimney and also assisting in centering the sections as they are laid. The sections forming the outer wall are corrugated upon one edge, as clearly appears in Fig. 3, to better hold the cement in laying them.

15 The sections of the inner wall or smoke-flue are each provided with an annular mortise, having a curved bottom on one end and a corresponding tenon having its end curved on the other end. This particular shape of mortise and tenon aids in adjusting the sections in laying them, as the wet cement can be readily worked out of the mortise by turning or rotating the section which is being laid.

20 The sections D of the inner wall of the smoke-flue fit within the seats s in the outer-wall sections, so that both the inner and outer wall sections are centered, as described. Thus arranged air passages or chambers are formed in the chimney, which practically surround the 25 smoke-flue. With the cap-piece in position, the upper ends of these passages are covered. (See Fig. 5.)

30 Laterally-opening outlets a are provided for the air-passages. These outlets are formed by forming notches in adjoining edges of a 35 pair of outer-wall sections. Thus formed the sections are not materially weakened in forming the openings therethrough.

35 The sections A' may be formed in the same 40 mold, the top section being placed in an inverted position.

45 The sections A'', having a combined pipe and ventilator opening therein, are provided. (See Figs. 1 and 4.) This combined pipe and 50 ventilator opening consists of a ring a', which is cast in the body of the wall-section, and a face-plate a'', having a central opening therethrough adapted to receive the stovepipe. A plurality of ventilator-openings communicating with the air-passages of the chimney 55 are grouped about the stovepipe-openings.

An inner wall or flue section D', having a pipe-opening d' therein, adapted to register with the pipe-opening in the face-plate a'', is 60 provided.

A section A''', having a ventilator a''' cast therein, is provided. This section is preferably located adjacent to the floor of the room. (See Fig. 1.)

65 When it is desired to connect a furnace to the chimney, a section A'''', having a ring-like thimble a'''' cast therein, is provided, and the inner wall or flue section is provided with a suitable pipe-opening adapted to register therewith, as clearly appears in Fig. 2. This

ring or thimble a'''' is provided with an outwardly-projecting lug f, through which the thumb-screw f' is arranged, by means of which the pipe may be secured in the thimble.

70 With the parts arranged as illustrated and described we secure a chimney which is practically fireproof and is also a very effective ventilator. The air and ventilator passages are sufficiently heated by the smoke-flue to insure the circulation thereof.

75 The parts of our improved chimney or stack are simple and economical to produce and very economical to assemble in constructing a chimney.

The combination thimble and ventilator is 80 very desirable in use in kitchens and the like, as it is so arranged as to carry away the vapors arising from cooking, although it is of advantage in other relations.

85 We have illustrated and described our improved chimney or stack in detail in the form preferred by us on account of the simplicity and economy of constructions of its parts and the ease and economy of assembling them in constructing a chimney, although we are aware 90 that it is capable of considerable structural variation without departing from our invention.

Having thus described our invention, what we claim as new, and desire to secure by Letters Patent, is—

1. In a chimney or stack, the combination of an exterior wall made up of rectangular sections having oppositely-arranged inwardly-facing curved seats therein; an inner wall or smoke-flue made up of tubular sections arranged in seats in said outer-wall sections, said inner and outer wall sections being arranged to overlap or break joints; a foundation having a clean-out chamber therein; cap and base pieces for said walls having central openings therethrough, and inwardly-projecting portions conformed to fit within said outer wall and about said inner wall or smoke-flue; outlet-openings through the sides of said outer wall toward the top, formed by notching the edges of two adjoining sections; an outer-wall section having an opening with a combined thimble and ventilator arranged therein; an inner-wall section having a pipe-opening adapted to register with said thimble; and an outer-wall section having a ventilator-opening therein, for the purpose specified.

2. In a chimney or stack, the combination of an exterior wall made up of rectangular sections having oppositely-arranged inwardly-facing curved seats therein; an inner wall or smoke-flue made up of tubular sections, said inner and outer wall sections being arranged to overlap or break joints; a foundation having a clean-out chamber therein; cap and base pieces for said walls having central openings therethrough, and inwardly-projecting portions conformed to fit within said outer wall and about said inner wall or smoke-flue; out-

let-openings through the sides of said outer wall toward the top; an outer-wall section having an opening with a combined thimble and ventilator arranged therein; an inner-wall section having a pipe-opening adapted to register with said thimble; and an outer-wall section having a ventilator-opening therein, for the purpose specified.

3. In a chimney or stack, the combination of an exterior wall made up of rectangular sections, having oppositely-arranged inwardly-curved seats therein; an inner wall or smoke-flue made up of tubular sections, said inner and outer wall sections being arranged to overlap or break joints; a foundation having a clean-out chamber therein; cap and base pieces for said walls having central openings therethrough, and inwardly-projecting portions conformed to fit within said outer wall and about said inner wall or smoke-flue; outlet-openings through the sides of said outer wall toward the top, formed by notching the edges of two adjoining sections; and an outer-wall section having a ventilator-opening therein, for the purpose specified.

4. In a chimney or stack, the combination of an exterior wall made up of rectangular sections having oppositely-arranged inwardly-facing curved seats therein; an inner wall or smoke-flue made up of tubular sections arranged in said seats in said outer-wall sections, said inner and outer wall sections being arranged to overlap or break joints; a foundation having a clean-out chamber therein; cap and base pieces for said walls having central openings therethrough and inwardly-projecting portions conformed to fit within said outer wall or smoke-flue; outlet-openings through the sides of said outer wall toward the top; and an outer-wall section having a ventilator-opening therein, for the purpose specified.

5. In a chimney or stack, the combination of an exterior wall made up of rectangular sections, having oppositely-arranged inwardly-facing curved seats therein; an inner wall or smoke-flue made up of tubular sections arranged in said seats in said outer-wall sections, said inner and outer wall sections being arranged to overlap or break joints; a foundation having a clean-out chamber therein; cap and base pieces for said walls having central openings therethrough, and inwardly-projecting portions conformed to fit within said outer wall and about said inner wall or smoke-flue; outlet-openings through the sides of said outer wall toward the top, formed by notching the edges of two adjoining sections; an outer-wall section having an opening with a combined thimble and ventilator arranged therein; an inner-wall section having a pipe-opening adapted to register with said thimble; for the purpose specified.

6. In a chimney or stack, the combination of an exterior wall made up of rectangular sections, having oppositely-arranged inwardly-

facing curved seats therein; an inner wall or smoke-flue made up of tubular sections arranged in said seats in said outer-wall sections, said inner and outer wall sections being arranged to overlap or break joints; a foundation having a clean-out chamber therein; cap and base pieces for said walls having central openings therethrough, and inwardly-projecting portions conformed to fit within said outer wall and about said inner wall or smoke-flue; and outlet-openings through the sides of said outer wall toward the top, for the purpose specified.

7. In a chimney or stack, the combination of an exterior wall made up of sections, having inwardly-facing curved seats therein; an inner wall or smoke-flue made up of tubular sections arranged in said seats in said outer-wall sections, said inner and outer wall sections being arranged to overlap or break joints; a cap-piece for said walls having a central opening therethrough, and inwardly-projecting portions conformed to fit within said outer wall and about said inner wall or smoke-flue; outlet-openings through the sides of said outer wall toward the top; an outer-wall section having an opening with a combined thimble and ventilator arranged therein; an inner-wall section having a pipe-opening adapted to register with said thimble; and a ventilating-opening in said outer wall, for the purpose specified.

8. In a chimney or stack, the combination of an exterior wall made up of sections having inwardly-facing curved seats therein; an inner wall or smoke-flue made up of tubular sections arranged in said seats in said outer-wall sections, said inner and outer wall sections being arranged to overlap or break joints; a cap-piece for said walls having a central opening therethrough, and inwardly-projecting portions conformed to fit within said outer wall and about said inner wall or smoke-flue; outlet-openings through the sides of said outer wall toward the top; suitable pipe-openings in said walls; and a ventilating-opening in said outer wall, for the purpose specified.

9. In a chimney or stack, the combination of an exterior wall made up of sections having inwardly-facing curved seats therein; an inner wall or smoke-flue made up of tubular sections arranged in said seats in said outer-wall sections, said inner and outer wall sections being arranged to overlap or break joints; a cap-piece for said walls having a central opening therethrough, and inwardly-projecting portions conformed to fit within said outer wall and about said inner wall or smoke-flue; outlet-openings through the sides of said outer wall toward the top; an outer-wall section having an opening with a combined thimble and ventilator arranged therein; and an inner-wall section having a pipe-opening adapted to register with said thimble, for the purpose specified.

10. In a chimney or stack, the combination of an exterior wall made up of sections having inwardly-facing curved seats therein; an inner wall or smoke-flue made up of tubular sections, said inner and outer wall sections being arranged to overlap or break joints; a cap-piece for said walls having a central opening therethrough, and inwardly-projecting portions conformed to fit within said outer wall and about said inner wall or smoke-flue; outlet-openings through the sides of said outer wall toward the top; and suitable pipe-openings in said walls, for the purpose specified.

11. In a chimney or stack, the combination of an exterior wall made up of sections having inwardly-facing curved seats therein; an inner wall or smoke-flue made up of tubular sections arranged in said seats in said outer-wall sections; a cap-piece for said walls having a central opening therethrough, and inwardly-projecting portions conformed to fit within said outer wall and about said inner wall or smoke-flue; outlet-openings through the sides of said outer wall toward the top; an outer-wall section having an opening with a combined thimble and ventilator arranged therein; an inner-wall section having a pipe-opening adapted to register with said thimble; and a ventilator-opening in said outer wall, for the purpose specified.

12. In a chimney or stack, the combination of an exterior wall made up of sections having inwardly-facing curved seats therein; an inner wall or smoke-flue made up of tubular sections arranged in said seats in said outer-wall sections; a cap-piece for said walls having a central opening therethrough, and inwardly-projecting portions conformed to fit within said outer wall and about said inner wall or smoke-flue; outlet-openings through the sides of said outer wall toward the top; suitable pipe-openings in said walls; and a ventilating-opening in said outer wall, for the purpose specified.

13. In a chimney or stack, the combination of an exterior wall made up of sections having inwardly-facing curved seats therein; an inner wall or smoke-flue made up of tubular sections arranged in said seats in said outer-wall sections; a cap-piece for said walls having a central opening therethrough, and inwardly-projecting portions conformed to fit within said outer wall and about said inner wall or smoke-flue; outlet-openings through the sides of said outer wall toward the top; an outer-wall section having an opening with a combined thimble and ventilator arranged therein; and an inner-wall section having a pipe-opening adapted to register with said thimble; for the purpose specified.

14. In a chimney or stack, the combination of an exterior wall made up of sections having inwardly-facing curved seats therein; an inner wall or smoke-flue made up of tubular sections arranged in said seats in said outer-wall

sections, a cap-piece for said walls having a central opening therethrough, and inwardly-projecting portions conformed to fit within said outer wall and about said inner wall or smoke-flue; outlet-openings through the sides of said outer wall toward the top; and suitable pipe-openings in said walls, for the purpose specified.

15. In a chimney or stack, the combination of an exterior wall made up of sections having inwardly-facing curved seats therein; an inner wall or smoke-flue made up of tubular sections arranged in said seats in said outer-wall sections, said inner and outer wall sections being arranged to overlap or break joints; outlet-openings through the sides of said outer wall toward the top; an outer-wall section having an opening with a combined thimble and ventilator arranged therein; an inner-wall section having a pipe-opening adapted to register with said thimble; and a ventilator-opening in said outer wall, for the purpose specified.

16. In a chimney or stack, the combination of an exterior wall made up of sections having inwardly-facing curved seats therein; an inner wall or smoke-flue made up of tubular sections arranged in said seats in said outer-wall sections, said inner and outer wall sections being arranged to overlap or break joints; outlet-openings through the sides of said outer wall toward the top; suitable pipe-openings in said walls; and a ventilating-opening in said outer wall, for the purpose specified.

17. In a chimney or stack, the combination of an exterior wall made up of sections having inwardly-facing curved seats therein; an inner wall or smoke-flue made up of tubular sections arranged in said seats in said outer-wall sections, said inner and outer wall sections being arranged to overlap or break joints; outlet-openings through the sides of said inner wall toward the top; an outer-wall section having an opening with a combined thimble and ventilator arranged therein; and an inner-wall section having a pipe-opening adapted to register with said thimble, for the purpose specified.

18. In a chimney or stack, the combination of an exterior wall made up of sections having inwardly-facing curved seats therein; an inner wall or smoke-flue made up of tubular sections arranged in said seats in said outer-wall sections, said inner and outer wall sections being arranged to overlap or break joints; outlet-openings through the sides of said outer wall toward the top; and suitable pipe-openings in said walls, for the purpose specified.

19. In a chimney or stack, the combination of an exterior wall made up of sections having inwardly-facing curved seats therein; an inner wall or smoke-flue made up of tubular sections arranged in said seats in said outer-wall sections; outlet-openings through the sides

of said outer wall toward the top; an outer-wall section having an opening with a combined thimble and ventilator arranged therein; an inner-wall section having a pipe-opening adapted to register with said thimble; and a ventilator-opening in said outer wall, for the purpose specified.

20. In a chimney or stack, the combination of an exterior wall made up of sections having inwardly-facing curved seats therein; an inner wall or smoke-flue made up of tubular sections arranged in said seats in said outer-wall sections; outlet-openings through the sides of said outer wall toward the top; suitable pipe-openings in said walls; and a ventilating-opening in said outer wall, for the purpose specified.

21. In a chimney or stack, the combination of an exterior wall made up of sections having inwardly-facing curved seats therein; an inner wall or smoke-flue made up of tubular sections arranged in said seats in said outer-wall sections; outlet-openings through the sides of said outer wall toward the top; an outer-wall section having an opening with a combined thimble and ventilator arranged therein; and an inner-wall section having a pipe-opening adapted to register with said thimble, for the purpose specified.

30. 22. In a chimney or stack, the combination of an exterior wall made up of sections having inwardly-facing curved seats therein; an inner wall or smoke-flue made up of tubular sections arranged in said seats in said outer-wall sections; outlet-openings through the sides of said outer wall toward the top; and suitable pipe-openings in said walls, for the purpose specified.

23. In a chimney or stack, the combination of an exterior wall made up of sections having inwardly-facing curved seats therein; an inner wall or smoke-flue made up of tubular sections arranged in said seats in said outer-wall sections, said inner and outer wall sections being arranged to overlap or break joints; a foundation having a clean-out chamber there-

in; a base-piece for said walls having a central opening therethrough, and inwardly-projecting portions conformed to fit within said outer wall and about said inner wall or smoke-flue; suitable pipe-openings in said walls; and a ventilating-opening in said outer wall, for the purpose specified.

24. In a chimney or stack, the combination of an exterior wall made up of sections having inwardly-facing curved seats therein; an inner wall or smoke-flue made up of tubular sections arranged in said seats in said outer-wall sections; a foundation having a clean-out chamber therein; a base-piece for said walls having a central opening therethrough, and inwardly-projecting portions conformed to fit within said outer wall and about said inner wall or smoke-flue; suitable pipe-openings in said walls; and a ventilating-opening in said outer wall, for the purpose specified.

25. In a chimney or stack, the combination of the exterior wall having inwardly-facing curved seats therein; an inner wall or smoke-flue, arranged in said seats, the portion enclosed in said outer wall about said smoke-flue forming ventilating-passages; outlet-openings for said ventilating-passages toward the top of said chimney; and an opening in said outer wall with a combined thimble and ventilator arranged therein, for the purpose specified.

26. In a chimney or stack, the combination of an exterior wall having inwardly-facing curved seats therein; an inner wall or smoke-flue arranged in said seats, the portions enclosed by said outer wall about said smoke-flue forming ventilating-passages; and suitable ventilating-openings for said walls, for the purpose specified.

In witness whereof we have hereunto set our hands in the presence of two witnesses.
